RADIO RECEIVING SYSTEM

Alfred N. Goldsmith, New York, N. Y., assignor
to Radio Corporation of America, a corporation
of Delaware

Application February 20, 1928, Serial No. 255,608

20 Claims. (Cl. 250—20)

This invention relates to the radio signalling art and deals more specifically with a method and system for minimizing the effects of fading in the reception of signals.

5 It has been proposed heretofore, in order to overcome fading, to place a plurality of separate receivers at different signal receiving points, and to combine the outputs of these several receivers into a common output circuit, to which the signal indicating mechanism is coupled. By virtue of this arrangement, if a signal is fading at one point, and the receiver at that point is therefore not picking up the required amount of signal energy, one of the other receivers supplements this deficiency in signal energy and thus uniform signal reception is had. However, in a system of this kind when the signal is fading in one of the receivers this receiver still functions to reproduce whatever undesirable noises may be present such as 10 atmospherics and other stray disturbances. These disturbances are amplified and fed to the aforementioned common output circuit, even though the receiver is not contributing useful signal energy to the final output.

20 It is therefore an object of this invention to provide a system of the character described in which the receiver, which is not yielding useful signal energy, automatically has its amplification or sensitivity reduced, so that the disturbing noises are not amplified and combined to any substantial degree with the useful signal, to confuse the same.

25 It is a further object of this invention to provide a radio receiving system having a plurality of separate receivers positioned at different points, in which all of the receivers except one have their sensitivity or amplification reduced, when that one receiver is functioning properly, to produce the desired amount of useful signal energy.

30 It is a further object of this invention to provide a signal receiving system employing a plurality of separate receivers all of which actuate a common indicating mechanism, in which system the overall static level is materially reduced.

35 And finally it is an object of this invention generally to improve the quality and reliability of a signal receiving system.

40 These and other objects of the invention will be readily apparent to those skilled in the art from the following description taken in connection with the accompanying drawing in which:

45 Fig. 1 is a diagrammatic representation of a system embodying this invention; and

Fig. 2 is a schematic view showing the details of one embodiment of this invention.

5 Referring in detail to Fig. 1 the principles of the operation of this system will be explained briefly.

10 Receiver 1 and receiver 2 each having its own antenna system are placed at any desirable signal receiving points, which points may be spaced by either a small or large distance. To the output circuit of one of the radio frequency amplifiers of receiver 1 is connected the input circuit of a sensitivity control unit 1, the output circuit of this sensitivity control 1 being connected to an input circuit of one of the radio frequency amplifiers of receiver 2. Similarly, the output circuit of one of the radio frequency amplifiers of receiver 2 is connected to the input circuit of the sensitivity control unit 2; and the output circuit of sensitivity control 2 is connected to an input circuit of one of the radio frequency amplifiers of receiver 1. The final audio output of receiver 1 and receiver 2 are then combined and led to the 15 signal indicating mechanism.

20 The operation of this system is as follows:

25 Let us assume that the signal is being received with normal strength by the receiver 1 and very little signal energy is being received by receiver 2. Under these conditions the sensitivity control 1, which is connected to the input circuit of a radio frequency amplifier of the receiver 2, serves to so bias the grid of such radio frequency amplifier, that receiver 2 has its amplification or sensitivity materially reduced. This prevents receiver 2 from amplifying atmospherics and other stray disturbances when that receiver is not contributing useful signal energy to the final output circuit. 30 Under these conditions, in view of the fact that receiver 2 is not intercepting substantial amount of signal energy, the sensitivity control 2, which is connected thereto, does not function to reduce the amplification or sensitivity of receiver 1.

35 However, in the event that receiving conditions change and the signal is now fading at 1, but is coming in strong at 2, the operation is reversed, and the sensitivity control 2 functions to reduce the amplification or sensitivity of receiver 1, thus 40 cutting down the amplification of undesirable disturbances, which are received at 1.

45 It will thus be seen, that by virtue of this arrangement, a plurality of receivers may be provided, all having their output circuits connected to a common signal indicating mechanism, in which the operation of a receiver which is not producing useful signal energy is nullified, if another receiver is operating under normal conditions.

50 In the event that signals are weak on each re-

ceiving set, the sensitivity controls 1 and 2 do not function, and the receivers 1 and 2, therefore, reproduce with maximum efficiency whatever signal energy they receive. Also, if the received signal is strong at both receivers 1 and 2, the sensitivity of both receivers is cut down correspondingly, so that there is not produced in the common output circuit more than the amount of energy desired to actuate the indicating mechanism.

Many forms of sensitivity control units are known in the art, and this unit, per se, forms no part of the present invention. The type of sensitivity control which is preferably used is shown as consisting of a vacuum tube having filament, grid and plate circuits. To the grid circuit is applied a voltage derived from the incoming carrier wave. In the plate circuit of this tube there is included a fixed resistance. Across this resistance there will appear a voltage drop, which varies in accordance with the strength of the incoming carrier wave. This voltage drop across the resistance is then applied to the grid circuit of the receiving set, in the form of a variable grid bias, and such variations in grid bias cause the sensitivity of the set to be varied, in exact proportion to the variation of the carrier intensity, but in inverse relationship. Thus, for example, when the carrier is strong, a high grid bias is applied to the amplifying tubes of the receiver, resulting in low sensitivity or low amplification; while when the carrier is weak, a small grid bias is applied to the amplifier tubes, resulting in high sensitivity or amplification.

Referring now in detail to Fig. 2, there is disclosed the details of a system embodying the present invention. Receiving antenna 10 has coupled to it the radio frequency amplifier 11 which is in turn coupled to an amplifying tube 12. Conductor 13, connected to the output circuit of amplifier 11, impresses the potential variations of the carrier current upon the grid of the tube 14. The blocking condenser 15 is provided to prevent the application of direct current voltages on the grid of the tube 14. In the output circuit of the tube 14 is connected the resistance 16, and the conductors 17 and 18 are connected across the terminals of resistance 16. The opposite ends of the conductors 17 and 18 are connected to the filament and grid respectively of the tube 20. This forms the electrical equivalent of connecting the resistance 16 between the filament and grid of the tube 20. It will thus be seen that the voltage variations across 16 are impressed upon the grid of tube 20, and these variations serve as the variable bias mentioned above. The detector 25 may be coupled to the radio frequency amplifying tube 12 in a manner well understood in the art and such detector may be followed by any desired number of audio frequency amplifiers. The amplifier 26 is shown, by way of example, and is coupled to the output circuit of the detector 25. The output circuit of 26 is coupled to the common output circuit as shown in the drawing.

A second receiving antenna 21 suitably positioned is coupled to the radio frequency amplifying tube 22, which is in turn coupled to the radio frequency amplifying tube 20. The conductor 30 is connected between the output circuit of the vacuum tube 20 and the grid of the tube 31. A blocking condenser 32 is provided in a manner well understood in the art. In the output circuit of the tube 31 is the resistance 33, which resistance is connected between the filament and grid of the

radio frequency amplifying tube 12 by means of conductors 34 and 35.

The detector 40 is coupled to the radio frequency amplifier 20 and to this is in turn coupled the audio frequency amplifier 41 having its output circuit connected to the common output as shown in the drawing.

This system operates as follows:

Assuming the signals to be strong in the antenna 10, the carrier voltage is impressed upon the grid of the tube 14 through the conductor 13, and this voltage causes a corresponding current to flow in the output circuit of the tube 14. The voltage drop across the resistance 16, resulting from the flow of current in the plate circuit of the tube 14, is impressed upon the grid of the tube 20. When the carrier in the output of the tube 12 is strong, the drop across the resistance 16 will be relatively large, and will cause a bias upon the grid of the tube 20, sufficient to reduce the sensitivity of the same, and thus nullify the action of the receiver 2. In the same way when the signals are strong in the receiver 2, and weak in the receiver 1, the voltages of the carrier received at 2 are impressed upon the sensitivity control tube 31 which produces corresponding voltage drops across the resistance 33, which voltage drops are applied to the grid of the tube 12 in the nature of a bias sufficient to cut down the amplification of this tube and thereby to nullify its action.

It is to be understood that the number of stages of radio frequency amplification and the particular types of receiving circuits used is unimportant for the purposes of the present invention for the reason that the present invention concerns itself with one stage of radio frequency amplification. Also, this invention may be applied to a superheterodyne receiver or any other well known type of receiver without departing from the spirit of this invention.

Various other changes will readily suggest themselves to those skilled in the art, and this invention is therefore not to be limited to details of structure or manipulation except as defined in the appended claims.

Having thus described my invention I claim:

1. A radio receiving system comprising, in combination, a first receiver and a second receiver, means for operating each of said receivers at the same frequency for simultaneously receiving the desired signal wave, a sensitivity control unit in circuit with said first receiver for governing the sensitivity of said second receiver, and a sensitivity control unit in circuit with said second receiver for governing the sensitivity of said first receiver.

2. A radio receiving system comprising in combination, a first receiver having vacuum tube amplifiers, a second receiver having vacuum tube amplifiers, said amplifiers having input and output circuits, each of said receivers operating at the same frequency, and a common tuned circuit operatively and symmetrically coupled to the amplifiers of both said receivers, a sensitivity control unit connected between the output circuit of only one of the vacuum tubes of said first receiver and the input circuit of one of the vacuum tubes of said second receiver.

3. A radio receiving system comprising in combination, a first receiver having amplifiers, a second receiver having vacuum tube amplifiers, each of said receivers operating at the same frequency, a first sensitivity control unit having input and output circuits, means connecting the output circuit of one of the vacuum tubes of said first am-

- plifier with the input circuit of said sensitivity control unit, means connecting the output circuit of said sensitivity control unit to the input circuit of one of the vacuum tubes of said second receiver, and a second sensitivity control unit similarly connected between the output of a vacuum tube of said second receiver and the input of a vacuum tube of said first receiver.
4. A radio receiving system comprising in combination, a first receiver having vacuum tube amplifiers, a second receiver having vacuum tube amplifiers, each of said receivers operating at the same frequency, a first sensitivity control unit having input and output circuits, means connecting the output circuit of one of the amplifiers of the first receiver with the input circuit of said first sensitivity control unit, means connecting the output circuit of said first sensitivity control unit with the input circuit of one of the amplifiers of said second receiver, a second sensitivity control unit having input and output circuits, means connecting the output circuit of one of the amplifiers of said second receiver with the input circuit of said second sensitivity control unit and means connecting the output circuit of said second sensitivity control unit with the input circuit of one of the amplifiers of said first receiver.
5. A radio receiving system comprising, in combination, a first receiver located at one point, a second receiver located at a second point, each of said receivers being tuned to the same wave length, means to govern the operation of said first receiver in accordance with the reception of said second receiver, said means being responsive only to said second receiver, and independent means responsive to only said first receiver to govern the operation of said last mentioned receiver in accordance with the reception of said first receiver.
6. A radio receiving system comprising in combination, a first receiver, a second receiver, said receivers being tuned to the same operating wave length, and a sensitivity control unit having an input and an output circuit, said input circuit being connected only to the output circuit of said first receiver, said output circuit of said unit being connected to said second receiver, and a common translating circuit coupled to and energized by both of said receivers.
7. A radio receiving system comprising in combination, a first receiver, a second receiver, said receivers being tuned to the same operating wave length, a first sensitivity control unit having an input and an output circuit, said input circuit being connected to said first receiver and said output circuit being connected to said second receiver, and a second sensitivity control unit having an input and an output circuit, said output circuit of said second unit being connected to said first receiver and said input circuit of said second unit being connected to said second receiver.
8. The method of eliminating fading in a radio receiving system which comprises, receiving signal energy of identical frequency at a plurality of separate points, utilizing a portion of said signal energy received at one point to control, before being detected, the reception at another of said points, utilizing a portion of said signal energy received at said last mentioned point to control, before being detected, the reception at said one point, and combining the received signal energy received at said plurality of points only when said energies simultaneously received at both said points are weak.
9. The method of signalling which includes collecting signal energy of identical frequency at a plurality of geographically separated points, amplifying the energy collected at each point, and utilizing a portion of the energy collected at one of the points for controlling in a predetermined manner, the amplification of the energy collected at another point only when there is an appreciable difference in signal strength received at said one point relative to that received at another separated point.
10. The method of signalling which includes collecting signal energy of identical frequency at a plurality of geographically separated points, amplifying the energy collected at each point, utilizing a portion of the energy collected at one point for varying in a predetermined manner the amplification of energy collected at another point; and utilizing a portion of the energy collected at said other point for varying, in similar manner, the amplification of the energy collected at said one point, but not utilizing at the same time both said portions of collected energy for the purposes specified.
11. The method of signalling which includes collecting signal energy at a pair of geographically separated points; separately amplifying the separately collected energies; rectifying separately, portions of the separately amplified energies; utilizing a portion of the rectified energy derived from one collecting point to vary the amplification of energy collected at the other point; and utilizing a portion of the separately rectified energy derived from the other separate collecting point, to control the amplification of energy separately collected at said one point.
12. A diversity receiving system comprising two antenna having different fading characteristics, a transmission path in circuit with each of the antennae, means to control the gain in each path solely in dependence upon the amplitude of the energy in the antenna associated with the other path, in order to magnify the ratio of the signal energies received on said antennae.
13. In a signalling system subject to variable transmission conditions, a plurality of receiver amplifiers each receiving and amplifying the same signal and so related to each other that the received signals vary differently at the several receiver amplifiers with variations in transmission conditions, a separate detector connected to each receiving amplifier, a utilization circuit, and means cross connecting said detectors and amplifiers to cause the receiver having the maximum output to feed a predetermined amount of energy to said utilization circuit and to reduce the output of another receiver amplifier of said system to said utilization circuit.
14. In a signalling system subject to variable transmission conditions, a plurality of receiver amplifiers each receiving the same signal and so related to each other that the received signals vary differently at the several receiver amplifiers with variations in transmission conditions, a separate detector connected to each receiving amplifier, a utilization circuit, means cross connecting said detectors and receiver amplifiers to automatically cause the receiver amplifier having the maximum output to feed a predetermined amount of energy to said utilization circuit and to reduce the amount of energy fed from another receiver amplifier having a weaker signal.
15. In a signaling system subject to variable

- transmission conditions, a plurality of receivers each receiving the same carrier frequency signal and so related to each other that the received signals vary differently at the several receivers with variations in transmission conditions, a receiving circuit, and means controlled by the received carrier component of a given receiver to connect that receiver to the receiving circuit exclusively of the others.
16. In a signaling system subject to variable transmission conditions, a plurality of receivers each receiving the same signal and so related to each other that the received signals vary differently at the several receivers with variations in transmission conditions, a receiving circuit, and means associated with said circuit to automatically select the receiver having the maximum signal output.
17. In a signaling system subject to variable transmission conditions, a plurality of receivers each receiving the same signal and so related to each other that the received signals vary differently at the several receivers with variations in transmission conditions, a receiving circuit, and means associated with said circuit to automatically select a receiver whose signal output conforms to a desired requirement.
18. In a signaling system subject to variable transmission conditions, a plurality of receivers each receiving the same signal and so related to each other that the received signals vary differently at the several receivers with variations in transmission conditions, a signal circuit common

to said receivers, and means responsive to the amplitude of the outputs of said receivers for automatically controlling the gain of at least one of said receivers to render substantially inoperative said one of said receivers when its output is materially lower than that of another of said receivers.

19. In combination, a plurality of signal receivers, and means for automatically controlling over a continuous range the gain of one of said receivers in response to the amplitude of the signal received in at least one of the other of said signal receivers to render substantially inoperative said one of said receivers when the amplitude of the signal wave received thereby is materially lower than the amplitude of the signal wave received by said other of said signal receivers.

20. In a signaling system subject to variable transmission conditions, a plurality of receivers each receiving the same signal and so related to each other that the received signals vary differently at the several receivers with variations in transmission conditions, and means for automatically controlling over a continuous range the gain of at least one of said receivers in response to the amplitude of the signal received in at least one of the respective others of said signal receivers to render substantially inoperative said one of said receivers when the amplitude of the signal wave received thereby is materially lower than the amplitude of the signal received by said one of the respective others of said signal receivers.

ALFRED N. GOLDSMITH.
